UNITED STATES PATENT OFFICE.

SWAN M. AKEYSON, OF LONG BEACH, CALIFORNIA.

PUMP VALVE.

Application filed April 21, 1928. Serial No. 271,699.

This invention relates to a valve particularly applicable to sludge pumps or other pumps carrying a high pressure and operating with a liquid containing coarse particles.

5 An object of my invention is to provide a valve having a rubber ring therein, which ring does not carry the full weight of the valve when the valve seats.

10 An advantage of the above mentioned arrangement is that the rubber ring will not hammer out as rapidly as in valves heretofore in use.

15 A further object of my invention is to provide a valve which can be quickly and easily assembled or disassembled for purposes of repair and replacement.

20 Other objects, advantages, and features of the invention may appear in the accompanying drawing, the subjoined detailed description and the appended claims.

In the drawing—

Fig. 1, is a side elevation of my valve.

Fig. 2, is a longitudinal sectional view of the same.

25 Referring more particularly to the drawing, the numeral 1 indicates the valve head, upon which the tapered seat 2 is formed. The head 1 and seat 2 are formed of metal and this seat provides the final seal as will be further described.

30 A plurality of guide wings 3, depend from the head 1, for the purpose of guiding the valve in its movement, all of which is usual and well known in the art.

35 A pin 4 rises from the head 1 and is preferably formed integral therewith which provides a very simple and inexpensive arrangement and one which is easily cast and machined.

40 A central bore 5 is formed in the pin 4, the purpose of which will be further described. A cap 6 rests on the head 1 and is slidably mounted on the pin 4. A rubber ring 7 is removably mounted in the cap 6, and the outer

45 periphery of the ring projects beyond the seat 2, so that the ring will first engage the seat in the pump. The advantage of this will be further described.

50 An annular groove 8 is provided in the head 1 to receive a bead 9 formed on the ring 7 to limit the upward slidable movement of the cap 6. On the pin 4 I provide a key 10

which extends through a bore 11 in the pin 4 and intersects the bore 5. An advantage of this last mentioned arrangement is to break 55 the vacuum caused by the reciprocation of the pin 4. In a groove such as is used in well known types of pumps, the key 10 is positioned slightly above the top of the cap 6 so that this cap can move upwardly when the 60 ring 7 strikes the seat in the pump thus permitting the metal seat 2 to engage and make the final seal.

The advantage of the movable cap is that the full weight of the valve does not rest 65 upon the ring 7 as the valve is closed the rubber ring carrying only the weight of the cap which being comparatively light materially increases the life of the ring which is not hammered to pieces or compressed due to 70 heavy blows and great weight. When it is necessary to disassemble the valve to replace the rubber ring or the like, it is only necessary to remove the key and slide the cap 6 off of the stem 4, which releases the rubber 75 ring and it can be quickly replaced and the parts again assembled.

Having described my invention, I claim:

1. A valve comprising a head, a stem rising from the head, a cap slidably mounted 80 on the stem and a rubber ring mounted in the cap and adapted to engage the seat upon which the valve rests.

2. A valve comprising a head, a stem rising from the head, a cap slidably mounted 85 on the stem and a rubber ring mounted in the cap and adapted to engage the seat upon which the valve rests, and a key extending through the stem above the cap to limit the upward movement thereof.

3. A valve comprising a head, a stem integral with the head and rising therefrom, a cap slidably mounted on the stem, a tapered seat on the head, a rubber ring in the cap, said ring normally projecting beyond the surface of the 95 seat on the head.

4. A valve comprising a head, a stem integral with the head and rising therefrom, a cap slidably mounted on the stem, a tapered seat on the head, a rubber ring in the cap, said ring normally projecting beyond the surface of the seat on the head, a key extending through the stem above the cap to limit the upward movement thereof.

5. A valve comprising a head, a stem integral with the head and rising therefrom, a cap slidably mounted on the stem, a tapered seat on the head, a rubber ring in the cap, said ring normally projecting beyond the surface of the seat on the head, a key extending through the stem above the cap to limit the

upward movement thereof, said head having an annular groove therein on the top thereof, a bead on the ring adapted to rest in the groove and a longitudinally extending bore in the stem.

In testimony whereof, I affix my signature.
SWAN M. AKEYSON.
